UNITED STATES PATENT OFFICE.

IVAN ELLWOOD, OF RED OAK, IOWA.

LAWN-MOWER.

No. 873,523.

Specification of Letters Patent.

Patented Dec. 10, 1907.

Application filed May 29, 1907. Serial No. 376,284.

To all whom it may concern:

Be it known that I, IVAN ELLWOOD, a citizen of the United States of America, residing at Red Oak, in the county of Montgomery 5 and State of Iowa, have invented new and useful Improvements in Lawn-Mowers, of which the following is a specification.

This invention relates to lawn mowers of that type embodying a rotary cutter having 10 spiral cutting blades and a coacting stationary knife carried by a frame mounted on ground wheels, such as disclosed in my prior application filed July 3, 1906, Serial Number 324,666.

One object of the present invention is to 15 provide a novel construction of frame and means for mounting the same and cutting devices upon the drive or ground wheels, whereby the necessity of employing a ground 20 roller is obviated and whereby the cutting devices are hung between the drive wheels in such position that the stationary cutter has its cutting edge lying substantially in the vertical plane of the axis of the drive wheels 25 or nearly so when the machine is in operation, the entire weight of the machine being carried upon the drive wheels to secure greater tractive and cutting power.

Another object is to provide improved 30 means for adjusting the cutting mechanism upon the frame and drive wheels, to position the stationary cutter so that it may swing under the action of the handle in the operation of the machine in a given range of movement 35 without altering its relation to the blades of the cutting wheel, and to provide a means whereby the cutting mechanism may be readily removed for sharpening and repairs.

With the above and other objects in view, 40 the invention consists of the novel construction, combination and arrangement of parts hereinafter fully described and claimed, reference being had to the accompanying drawings, in which:

Figure 1 is a rear elevation of a lawn 45 mower embodying my invention, parts being broken away to better show the construction. Fig. 2 is a section on line 2—2 of Fig. 1. Fig. 3 is a section on line 3—3 of Fig. 1. Fig. 4 is an outer end elevation showing one of the ground wheels and associated parts of the frame. Fig. 5 is an irregular vertical section on line 5—5 of Fig. 2. Fig. 6 is an elevation 55 of the casing removed from the wheel and a vertical section through the adjustable hous-

ing and gear connection between the rotary cutter shaft and driving train. Fig. 7 is a detail showing the adjustable connection of the handle with its yoke. Fig. 8 is a detail 60 section on line 8—8 of Fig. 2.

Referring to the drawings, 1 represents the ground or drive wheels of the mower, each having a hub 2 carrying a bearing box or bushing 3 for revoluble movement on an axle 4. The bolts 4 are mounted in the sides of the supporting frame, each side of which frame is formed by inner and outer hangers composed of sets or pairs of divergently arranged arms 5 and 6, the front and rear arms 70 of the hangers at both sides of the machine being connected and braced by transverse rods or bars 6' and 7, integral with or secured to the arms in any preferred manner. The outer converging ends of each set of arms 6 75 are integrally connected, and are provided at their point of junction with a proper opening to receive the outer end of the axle bolt 4. The inner converging ends of each set of hanger arms 5 are integral with or fixed to a 80 gear casing 8 closed at its inner side by a cover plate 9 detachably secured thereto by bolts or other fastenings 10, which cover plate is provided with an opening for the inner end or head of the bolt 4, which is retained in position by a clamping nut 11 and a washer 12.

The inner end of the hub 2 extends into the casing, which is loosely mounted thereon, and also loosely mounted on the hub within 90 the casing is a master drive wheel 13, on the inner side of which is a ratchet wheel 14 fixed to the hub, the wheel 13 being provided with gravity-pawls 15 to engage the teeth of the ratchet wheel, the construction and arrangement of the pawls and teeth being such as to adapt the ratchet wheel to impart motion to the master drive wheel when the machine is propelled forward and allow the pawls to ride over the teeth without affecting said master 95 drive gear to permit the machine to be backed or drawn rearwardly without operating the cutting mechanism.

The gear 13 meshes with a pinion 16 arranged within a partially circular extension 105 17 of the casing located at the lower front portion thereof, which extension projects inwardly and laterally beyond the casing to form a housing 17' for a power transmitting gear 18, said pinion and gear being mounted 110 on a common shaft 19 journaled in the end walls of the extension 17 and its companion

housing portion 17'. The rear or open side of the housing 17' has the end portions of its annular body or rim spaced from the open inner side of the casing 8 to provide an intervening slot 20 to permit of the convenient application and removal of the cover plate 9 without interference.

The two power transmission gears 18 at the opposite sides of the frame mesh with 10 gears 21 carried by collars 22 fixed upon the rotary cutter shaft 23, which is journaled at its ends in bracket arms or plates 24. The rotary cutter consists of spiral cutting blades 25 connected at their ends by arms 26 to the 15 collars 22 of the gears 21, said blades being braced at one or more places equidistant from their ends by a secondary set of spider arms 27 carried by a collar or sleeve 28 embracing the shaft. Instead of the shaft 23 20 being revoluble in the bracket plates or arms 24, said shaft may be fixed in said arms and the hubs or sleeves 22 arranged to turn thereon to rotate the cutting blades around the stationary shaft, as will be readily understood.

The bracket arms 24 are arranged on the inner sides of the casings 8 at a normal downward and rearward angle obliquely to the axes of the drive wheels, and carry at their 30 lower ends the supporting plate or bar 29 of the stationary cutting knife or blade 30. The bar 29 is provided at each end with an extension or upright bracket piece 31 fulcrumed to the adjacent hanger arm 24 by 35 screws 32 or other suitable pivot connections, and to these bracket pieces are connected adjusting screws 32 mounted in bearings 33, whereby the stationary knife may be adjusted on its pivotal connections to set it in 40 proper relation to the cutting wheel. The bracket arms 24 project through the space or slot 20 between the cover plate of each casing and the upper end of the body wall of the housing 17', and are mounted in such manner 45 as to be adjustable to regulate the height of cut and to maintain the cutting edge of the stationary knife 30 substantially in the vertical plane of the axes of the drive wheels and to permit the cutting mechanism as a whole 50 to be quickly and conveniently detached for sharpening or repairs and as readily reapplied after being refitted for work.

Projecting laterally from each casing and supported respectively by the cover plate 9 55 and an apertured lug or ear 8' on the bottom of the casing are upper and lower guide bolts 34, which extend through slots 35 in the arms 24, a pair of such slots being formed in each arm, one above and the other below the shaft 60 23, thus providing for the adjustment of said bracket arms in a vertical plane to raise and lower the cutting mechanism, the bolts being provided with nuts 36 by which the bracket arms may be clamped in adjusted position.

65 The slots 35 are of the same arcuation as gear

wheel 18, but with opposite curvature, so that pinion 21 will always properly engage gear 18 at any position of adjustment to regulate the height of cut, it being understood that the cutting mechanism may be 70 bodily adjusted vertically upward or downward by a sliding motion of the bracket arms 24 to the extent limited by the slots 35, and that owing to the form and arrangement of said slots the bracket arms will always maintain the same relation between the gears 18 and 21, irrespective of the height of the cutting mechanism above the ground surface. A casing or housing 37 incloses each pinion 21 and is open at its forward side facing the 80 open rear side of the housing 17' and provided with curved or arcuate wings or extensions 38 to overlap the wall of the housing and maintain a close intervening joint. At its upper and lower portion each casing 37 is 85 provided with guide flanges 39 engaged by clips or guide members 40 on the arm 24, by which the said casing 37 is permitted to oscillate in a plane concentric with the axis of the gear 18. It will thus be understood that as 90 the bracket arms are adjusted up and down the casing 37 will turn or rotate in its guides to maintain its proper connection with the housing 17', and that the necessary corresponding adjustment of the gearing effected 95 by the change in position of the pinions 21 is effected in an easy and convenient manner.

The handle 41 of the machine is connected in the usual manner to the frame by a yoke, the arms 42 of which are attached at their 100 forward ends to the rear arms of the outer hangers in a rigid manner either by fastening them to said arms, as by bolts, or forming them integrally therewith. The rear ends of the yoke arms terminate in parallel portions 105 43 receiving the forward end of the handle 41 which is pivoted thereto by a bolt 44 having the usual clamping nut 45. The bolt 44 is located in rear of the forward extremity of the handle, through which forward extremity 110 extends a bolt 46 adjustable in arcuate slots 47 formed in said portions 43 and carrying a clamping nut 48 for fastening it in adjusted position. By this construction the handle 115 may be adjusted to lie at any angle relative to the frame to the necessary degree without varying the position of the frame or parts of the cutting mechanism.

It will be seen from the foregoing description that the cutting mechanism is adjustable on the frame to move the cutters closer to or farther from the ground surface to regulate the height of cut, and can be entirely removed from the frame to facilitate the sharpening of same or for any other purpose, and that the arc of adjustment is such that the gears 18 and 21 will always be properly engaged, whatever the adjustment of the cutting mechanism with reference to the frame, and further that the mode of constructing 125 130

the frame insures great strength, rigidity and durability. The ledger plate is so hung relative to the axis of the drive wheels that the edge of the stationary knife lies in the 5 vertical plane of said axis, or nearly so, when in operation. In practice, it is preferred to set the parts so that the distance of the said stationary knife from the axis of the drive wheel relative to the length of the handle is 10 approximately in a ratio of one to twelve, the handle being about forty-eight inches from the center of the drive wheels and the stationary knife about four inches, in a machine of the ordinary size, so that a variation 15 of as much as a foot in the distance of the handle from the ground surface while the machine is in operation will cause the knife to move but an inch in the arc of a circle concentric with the axis of the drive wheels, enabling 20 the handle to be manipulated in operation without changing the position of the stationary cutting knife to any material extent, the variation being so slight in the adjustment and height of cut as to be practically imperceptible. Accordingly, the necessity 25 of employing the usual ground roller as a secondary support and to regulate the height of cut is obviated. It will further be observed that as the weight of the frame and 30 drive gearing is supported solely by the drive wheels the tractive and driving power of the latter is increased to a maximum extent.

The construction which enables the usual ground roller to be dispensed with also simplifies and lightens the machine, thus adapting 35 it to be manufactured at a lower cost.

Having thus described the invention, what is claimed as new, is:—

1. In a lawn mower, a frame provided 40 with side members, each including a gear casing, ground wheels rotatably mounted on said side members and having hubs projecting into the casings, cutting mechanism, including stationary and rotary cutting devices, brackets detachably and adjustably connected with the casings and carrying said cutting mechanism, clutch gearing arranged within each casing, and gear trains at each side of the frame for operating the rotary 45 cutter, each including a gear member supported upon the adjacent bracket for adjustment therewith.

2. In a lawn mower, the combination of 50 a frame provided with side members, each including a gear casing, ground wheels rotatably mounted on said side members and provided with hubs projecting into the casings, clutch gearing within each casing connected with the hub of the drive wheel, power transmitting gears mounted within 55 the casings and driven by the clutch gearing, a cutter frame provided with bracket arms detachably and adjustably mounted upon

the casings, a stationary cutter carried thereby, a revoluble cutter supported by the 65 bracket arms, and gears upon the bracket arms for transmitting motion to the revoluble cutter from the transmission gears.

3. In a lawn mower, the combination of 70 a frame provided with side members, each including a gear casing, ground wheels rotatably mounted on said side members and having hubs projecting into the casings, a supporting bar, brackets carrying said bar and mounted for adjustment in an arcuate 75 path upon said respective gear casings, a stationary cutter carried by the supporting bar, a revoluble cutter having its shaft supported by the bracket arms and provided with gears, clutch gearing within each casing 80 driven by the hub of the adjacent ground wheel, and a gear train upon each casing for transmitting motion from the clutch gearing to the contiguous gear on the cutter shaft.

4. In a lawn mower, a frame provided 85 with side members, each including a gear casing, drive wheels rotatably mounted on said side members, clutch and transmission gearing within each casing driven from the associated drive wheel, bracket arms, cutting 90 mechanism comprising relatively stationary and rotary cutters carried by said bracket arms, means adjustably and detachably connecting said arms for adjustment in an arcuate path on the casings, and 95 gears supported by the bracket arms and driven by the transmission gearing for driving the rotary cutter.

5. In a lawn mower, the combination of 100 a frame provided with side members, each including a gear casing, drive wheels rotatably mounted on said side members and having hubs projecting into the gear casings, gearing within each gear casing having a ratchet connection with the hub of the adjacent 105 wheel, and including a transmission gear inclosed by a portion of said casing and arranged upon the inner side thereof, bracket arms, relatively stationary and rotary cutters carried by said bracket arms, said rotary cutter being revolubly mounted upon said arms and provided with gears meshing with the transmission gears, and means adjustably and detachably connecting the bracket arms 110 with the casings above and below the gears upon the rotary cutter, said means being arranged to permit adjustment of said arms in an arcuate path to maintain a meshing engagement of said gears.

In testimony whereof, I affix my signature in presence of two witnesses.

IVAN ELLWOOD.
